(57) **CLAIM**

I claim the ornamental design for tilttable heating device, as shown and described.

DESCRIPTION

FIG. 1 is a top, front perspective view of a tilttable heating device of the present invention.

FIG. 2 is a front view of the tilttable heating device depicted in FIG. 1.

FIG. 3 is a right, side view of the tilttable heating device depicted in FIG. 1.

FIG. 4 is a rear view of the tilttable heating device depicted in FIG. 1.

FIG. 5 is a left, side view of the tilttable heating device depicted in FIG. 1.

FIG. 6 is a top view of the tilttable heating device depicted in FIG. 1; and,

FIG. 7 is a bottom view of the tilttable heating device depicted in FIG. 1.

The broken lines in the drawings illustrate portions of the tilttable heating device that form no part of the claimed design.
